UNITED STATES PATENT OFFICE

138,239

DESIGN FOR A SWIVEL BODY ELEMENT

Fred E. Anderson, Taft, Oreg.

Application January 19, 1944, Serial No. 112,262
In Canada September 2, 1943

Term of patent 3½ years

(Cl. D55—1)

To all whom it may concern:

Be it known that I, Fred E. Anderson, citizen of the United States of America, residing at the city of Taft, State of Oregon, have invented a new, original, and ornamental Design entitled Swivel Body Element, of which the following is a specification, reference being had to the accompanying drawing, forming a part thereof.

Fig. 1 is a top plan view of a swivel body element showing my new design;

Fig. 2 is a sectional view taken on line 2—2 of Fig. 1;

Fig. 3 is a side elevational view; and

Fig. 4 is an end elevational view taken from the right of Fig. 1.

I claim:

The ornamental design for a swivel body element, as shown.

FRED E. ANDERSON.
